UNITED STATES PATENT OFFICE

LEO SICHEL, OF ST. GEORGE, NEW YORK

MUTUAL COUNTERBALANCING OF TOOL HOLDERS OF GRINDING MACHINES

Application filed September 19, 1928. Serial No. 306,373.

This invention relates generally to machinery and has more particular reference to a novel mutual counterbalancing device for tool holders, especially adapted for grinding machines.

The invention has for an object the provision of a device of the class mentioned which is of simple durable construction, desirable and efficient in use, and which can be manufactured and sold at a reasonable cost.

Machinery for grinding guide ways or flat bearings on machines such as lathes, planers etc. as well as other machinery, is customarily made of a design in which a one piece double tool arm radially carries a plurality of grinding heads or tool holders and is vertically slidably mounted on a column.

The construction allows of bringing the tool heads on the two arms of the double tool arm successively into the working position i. e. to that side of the column where the work is located, as well as of adjusting the height of double tool arms on the column and of moving the same towards the work.

The double tool arm must be of substantial design in order to counteract torsional and other deflectional stresses. The same is therefore of considerable mass and weight and to accomplish with ease any height adjustment or new position along the column it becomes necessary to counterbalance the same.

Such counterbalancing has in the past mostly been effected thru the action of gravity and by means of counterweights. But such counterweights are a great inconvenience and expense as they have either to be very heavy or to traverse a long way in response to any movement of the tool arm along the column in conformity with the well known law of "force multiplied by distance." It is thus hardly possible to build this design of machinery without costly foundations to take up the counterweight apparatus for holding and moving the same, and in each case the weight and apparatus as added to the machine has no other useful function than that to counterbalance the double arm by gravity.

In one form of guide way or flat bearing

grinding machines known as stationary work machines or traversing column types machines in which the column with the double tool arm reciprocates on a support as contrasted with the one in which the same is stationary and the work is traversed on a table, it is impractical to balance the tool arm by gravity of counterweights as in the last mentioned class of machines since such a design would necessitate the constant transportation of the counterweight during the operation of the machine.

The object of this invention is to entirely eliminate additional weights for counterbalancing by gravity, by making the double tool arm in two independent parts each section with its grinding head or heads mounted thereon being a separate unit, and to use the weight of one to directly counterbalance the weight of the other within any convenient limits.

This procedure while greatly simplifying the design of such machinery does not in the least abstract from its utility or adaptability since only one arm section with its grinding heads or tool holders is used at any one time and it is immaterial which position the other arm occupies along the column during such time.

For further comprehension of the invention, and of the object and advantages thereof, reference will be had to the following description and accompanying drawings, and to the appended claims in which the various novel features of the invention are more particularly set forth.

In the accompanying drawings forming a material part of this disclosure:—

Fig. 1 is an end elevational view of a machine constructed according to this invention.

Fig. 2 is a side elevational view thereof.

Fig. 3 is a plan view of a column and tool arm sections used in the device.

Fig. 4 is a fragmentary enlarged detail view of a portion of Fig. 3.

Fig. 5 is a horizontal sectional view taken on the line 5—5 of Fig. 1.

Fig. 6 is a perspective view of a gravity point bracket used on the arm sections.

The reference numeral 10 indicates generally the working table of a grinding machine of any design and construction having apparatus 11 for operating the table, and 5 a main base 12. A column 13 is rotatively mounted on the base 12 and has a co-axial shaft 14 provided with a gear 15 meshing with another gear 16 fixed on a shaft 17 rotatively mounted in the base and extending 10 therefrom and provided on its free end with a hand wheel 18. This hand wheel may be turned for rotating the column 13.

A double tool arm 19, formed of separate 15 sections 19^a and 19^b is slidably arranged on the column 13. The section 19^a carries a tool head 21. The column 13 is provided with projecting ribs 22 engaging in cut-outs 22^a formed in the tool sections for guiding the tool sections in their slidable movements. 20 The tool sections are provided with ball bearing rollers 23 engaging against these projections 22 for protecting the latter against side play.

Attached on the top of the column 13 is a 25 guide member 24 and a main support leg 25 is slidably mounted in this guide member and held in fixed positions by a screw 26. The connection between the main support 25 and the guide 24 consists in a dove-tailed 30 tongue and groove engagement 27. The main support leg 25 supports a pulley support bar 28 horizontally arranged. A large pulley 29 is rotatively mounted in the support bar on one side of the leg 25. Idler pulleys 30 and 35 30' are mounted on the support bar 28. A cable or chain 31 extends over these pulleys and has one of its ends connected with a gravity point bracket 42 attached on the arm section 19^b at its center of gravity and its 40 other end connected with a gravity point bracket 42', attached on the arm section 19^a at its center of gravity.

The pulley 29 acts as a common point of 45 suspension for the arm section. These arm sections are substantially balanced so that they may be easily moved, counterbalancing each other.

The gravity point bracket 42 consists of 50 an attachment portion having an aperture 43 for receiving a fastening cap screw, as 44, and a toothed lower edge 45 for engaging a complementary recess in the arm sections, and an extension portion 46 which is provided with a dove-tailed groove 47. An eye member 48 is slidably arranged in this groove and capable of being fixed in desired positions by 55 a set screw 49. The cable 31 is attached to the eye member 48. The brackets 42 may be set in various rotated positions as determined by the teeth 45.

Racks 32 are attached at the sides of the 60 column 13 and mesh with gears 33 rotatively supported on the arm sections 19^a and 19^b integral with worm wheels 33' which in turn mesh with worms 34 fixed on shafts 35 and

35' rotatively mounted within the arm sections 19^a and 19^b respectively and extending therefrom. The hand wheels 36 and 36' are fixed on the free end of these shafts. Shafts 35 and 35' are secured in a pivoted bearing 35^a 70 to allow worms 34 to be moved out of engagement of worm wheels 33' whenever desired. The arm section 19^a is formed with dove-tailed tongues 37 engaged by support arms 38.

In operation of the device the tool head 20 is first arranged over the work table, and lowered by the operation of the hand wheel 36'. Material to be worked upon is secured on the work table 10 and the apparatus 11 75 operated for moving the work material while engaged with the tool head. Upon completion of the work with this tool head the section 19^b may be raised. It is pointed out that the arm section 19^a counterbalances arm section 19^b for ease in raising either of these 80 sections.

The hand wheel 18 is then operated for 85 rotating the column through an angle of 180 degrees. Then the hand wheel 36 may be 90 operated for lowering the arm section 19^a against the work on the work table. Various tools may be engaged within the tool heads and this may affect the centers of gravity of the arm sections. For this reason the eye members 48 may be moved to the new 95 gravity positions and the main support leg 25 may be adjusted to a new position for changing the common point of suspension. The pulley support bar 28 is firmly held by auxiliary braces 39 acting against the column 100 13. These braces may be fixed in desired positions by screws 40 acting in slots 40^a.

It is also obvious that the counterbalancing by means of a chain or rope is only an example shown to illustrate the principal of 105 the device and other forms of mechanism such as for instance beams, knife points, universal joints or other means might be interposed for securing a counterbalancing and sliding along the vertical column 13 of the 110 two tool support arms without in the least detracting from the character of the invention.

It is likewise immaterial to the character 115 of the invention how many grinding heads are carried on each of the sections. It is furthermore immaterial which form is given to the vertical column 13 as well as by which means the arm sections are given their sliding or positioning means along the 120 column.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what 125

I claim as new, and desire to secure by United States Letters Patent is:—

1. A device of the class described, comprising a base, a work table mounted thereon, a column vertically supported on the base, a pair of arm sections slidably mounted on the column, tool heads supported on the said arm sections, and a means for counterbalancing one of the arm sections against the other. 10
2. A device of the class described, comprising a base, a work table mounted thereon, a column vertically supported on the base, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension. 15
3. A device of the class described, comprising a base, a work table mounted thereon, a column vertically supported on the base, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads. 20
4. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads. 25
5. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads. 30
6. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads, said latter means comprising a horizontal support bar adjustably mounted on said column and supporting pulleys, and said flexible member engaging over said pulleys. 35
7. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads, said latter means comprising a horizontal support bar adjustably mounted on said column and supporting pulleys, said flexible member engaging over said pulleys, and reinforcing brackets attached to the ends of the support bar and movably mounted on the column. 40
8. In a device of the class described, a work table, a column supported in the vicinity of the work table, a pair of arm sections slidably supported upon said column, tool heads supported on said arm sections and engageable with work on said work table, and means for causing the tool heads to counterbalance each other so that one of the said tool heads may be easily drawn into an operative position upon moving the other to an inoperative position. 45
9. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads, said latter means comprising a horizontal support bar adjustably mounted on said column and supporting pulleys, said flexible member engaging over said pulleys, said adjustable mounting comprising a guide member attached on said column, and a support leg attached to said support bar and slidably movable in said guide member. 50
10. In a device of the class described, a work table, a column supported in the vicinity of the work table, a pair of arm sections slidably supported upon said column, tool heads supported on said arm sections and engageable with work on said work table, and means for causing the tool heads to counterbalance each other so that one of the said tool heads may be easily drawn into an operative position upon moving the other to an inoperative position. 55
11. A device of the class described, comprising a base, a work table mounted thereon, a column vertically supported on the base and arranged for rotation, a pair of arm sections slidably mounted on the column, tool heads supported on the said arm sections, and a means for counterbalancing one of the arm sections against the other consisting of a flexible member connected between the centers of gravity of the arm sections and movably supported at a common point of suspension, and a means of changing the position of the said common point of suspension for rebalancing the arm sections after tools are engaged in the said tool heads, said latter means comprising a horizontal support bar adjustably mounted on said column and supporting pulleys, said flexible member engaging over said pulleys, said adjustable mounting comprising a guide member attached on said column, and a support leg attached to said support bar and slidably movable in said guide member. 60
12. In a device of the class described, a work table, a column supported in the vicinity of the work table, a pair of arm sections slidably supported upon said column, tool heads supported on said arm sections and engageable with work on said work table, and means for causing the tool heads to counterbalance each other so that one of the said tool heads may be easily drawn into an operative position upon moving the other to an inoperative position. 65

9. In a device of the class described, a work
table, a column supported in the vicinity of
the work table, a pair of arm sections slidably
supported upon said column, tool heads sup-
5 ported on said arm sections and engageable
with work on said tool heads in the opposite
direction to the other and causing the tool
heads to counterbalance each other so that
one of the said tool heads may be easily drawn
10 into an operative position upon moving the
other to an inoperative position.

In testimony whereof I have affixed my sig-
nature.

LEO SICHEL.
